United States Patent Office

Des. 209,053
Patented Oct. 31, 1967

209,053

TEST PROBE

Lawrence J. Link, Jr., Columbia Heights, Minn., assignor
to Honeywell Inc., Minneapolis, Minn., a corporation
of Delaware

Filed Sept. 27, 1966, Ser. No. 4,051

Term of patent 14 years

(Cl. D26—1)

FIG. 1

FIG. 2

FIG. 3

FIGURE 1 is a plan view of a test probe embodying my new design;

FIGURE 2 is a side elevational view taken from below as seen in FIGURE 1; and

FIGURE 3 is a bottom view of my new design.

The essential features of the design reside in the solid line portions.

I claim:

The ornamental design for a test probe, substantially as shown and described.
